US00D482717S

(12) **United States Design Patent** (10) Patent No.: **US D482,717 S**
 Lane et al. (45) Date of Patent: **** Nov. 25, 2003**

(54) **EYEGLASSES**

(75) Inventors: **Henry Welling Lane**, San Luis Obispo, CA (US); **Kieran Steven Hardy**, San Luis Obispo, CA (US)

(73) Assignee: **Dioptrics Medical Products, Inc.**, San Luis Obispo, CA (US)

(**) Term: **14 Years**

(21) Appl. No.: **29/157,098**

(22) Filed: **Mar. 12, 2002**

(51) LOC (7) Cl. **16-06**

(52) U.S. Cl. **D16/321; D16/326**

(58) Field of Search **D16/101, 300-330, D16/335-337, 339-340, 900; D29/109, 110; 351/41, 44, 51, 52, 57-61, 121, 123, 153, 156-158; 2/426, 448, 449, 428, 430, 436, 444**

(57) **CLAIM**

We claim the ornamental design for eyeglasses, as shown and described.

DESCRIPTION

FIG. 1 is a top perspective view of eyeglasses showing of my new design;
 FIG. 2 is a front elevation view of eyeglasses thereof;
 FIG. 3 is a rear elevation view of eyeglasses thereof;
 FIG. 4 is a top view of eyeglasses thereof;
 FIG. 5 is a bottom view of eyeglasses thereof; and,
 FIG. 6 is a left side elevation view of eyeglasses thereof, the right side being a mirror image of the left side.
